UNITED STATES PATENT OFFICE

153,755

DESIGN FOR A JEWELRY CHAIN

Paul Bardach, Providence, R. I.

Application October 9, 1948, Serial No. 149,059

Term of patent 3½ years

(Cl. D45—16)

To all whom it may concern:

Be it known that I, Paul Bardach, a citizen of the United States, residing at Providence in the county of Providence and State of Rhode Island, have invented a new, original, and ornamental Design for Jewelry Chain, of which the following is a specification, reference being had to the accompanying drawing, constituting a part thereof.

Fig. 1 is a top plan view of a jewelry chain, showing my new design; and

Fig. 2 is a side view thereof.

I claim:

The ornamental design for a jewelry chain, substantially as shown.

PAUL BARDAK.
